UNITED STATES PATENT OFFICE

ALANSON P. BRUSH, OF DETROIT, MICHIGAN

BOAT

Application filed May 21, 1928. Serial No. 279,348.

This invention relates to boats and particularly to that type thereof commonly known as hydroplanes, the principal object being to provide a boat of this type that will have a 5 minimum of wetted surfaces and maximum stability.

In boats of this type, which differ from the ordinary displacement type of boat in that they depend upon the reaction of the water 10 against their bottoms due to their speed to raise them sufficiently out of the water so that they skim along or over the top thereof rather than through the water, it has been found necessary in order to obtain longitudinal 15 stability of the boat, so that it will not jump while traveling over the water, to provide one or more steps in the bottom surface thereof, so that when the boat is traveling over the water it has two distinct points of 20 support on the water longitudinally spaced from each other. Furthermore, as it is necessary for the successful operation of a boat of this type that it travel at a relatively high speed in order that it may plane sufficiently 25 to get on top of the water rather than pass through the same, it is necessary in order to obtain lateral stability to make the boat wider than would otherwise be necessary to obtain sufficient planing surfaces for the 30 proper lifting or planing thereof.

Furthermore, in this type of boat as heretofore constructed, the angle of the bottom or planing surfaces changes with the speed of the boat due to the fact the rear planing 35 surface travels over the water which has immediately previously been traveled over by the forward planing surface and such water has been displaced from its normal level an amount dependent upon the displacement of 40 the first planing surface in the water, which displacement is usually a function of the speed and other characteristics of the boat.

It is another object of the present invention to provide a boat of the type described 45 so constructed as to have a greater longitudinal stability than hydroplanes of conventional construction and to have a greater lateral stability than hydroplanes of the conventional construction, and yet in which it is 50 possible to have a smaller wetted surface,

thereby decreasing the friction between the boat and the water during operation of the same and enabling the boat to attain higher speed as a result.

It is another object to provide a boat of 55 the type described in which the planing surfaces are so arranged with respect to each other that none of them are subjected to the water disturbed by another thereof.

A further object is to provide a boat that 60 presents maximum stability both at rest and while running.

The above being among the objects of the 65 present invention the same consists in certain features of construction and combinations of parts to be hereinafter described with reference to the accompanying drawings, and then claimed, having the above and other objects in view.

In the accompanying drawings which illustrate suitable embodiments of the present invention and in which like numerals refer to like parts throughout the several different views,—

Fig. 1 is a more or less diagrammatic side 75 elevation of a hydroplane constructed in accordance with the present invention.

Fig. 2 is a plan view of the hydroplane shown in Fig. 1.

Figs. 3, 4, 5 and 6 are sections taken on the 80 lines 3, 4, 5 and 6 respectively of Fig. 1.

As illustrated in Fig. 1 the boat is provided with a single step in its bottom at 10. The hull is also provided on each side with two chines 11 and 12. The lower chine 11 terminates at the step 10 near or in the plane of the keel and at a point approximately midway between the keel and the side of the boat. The chine 12 at the point where it reaches the step 10 longitudinally of the boat 85 is preferably positioned substantially above the top of the step 10 as shown and continues rearwardly therefrom to the stern 14 which it reaches at substantially the same horizontal level, when the boat is in operation, as the bottom of the step 10. The surfaces 15 and 15' between the chines 11 and 12 extend upwardly and outwardly from the chines 11 so that when the boat is in operation and skimming over the water, the only 90

surface thereof in contact with the water forwardly of the step 10 is that surface between the chines 11 for a short distance forwardly of the step 10. This surface is gradually flattened towards the stern of the boat 5 until at the step 10 it provides a substantially flat planing surface 16, as best illustrated in Fig. 4, while the surfaces 15 and 15' extending upwardly and outwardly therefrom 10 are entirely clear of the water at such point. The surface 17 which extends rearwardly from the step 10 between the extended lines of the chines 11 preferably turns upwardly a slight amount towards the stern 14 where 15 it terminates, but in no case is it desirable that it extend rearwardly from the top of the step 10 below a horizontal line through the top of the step 10 when the boat is in proper planing position.

20 The surfaces 15 rearwardly of the step 10 gradually flatten out and as they are positioned below the surface 17, they present adjacent the stern 14 two spaced planing surfaces 18 extending from the outer edge of the hull inwardly to the corresponding edge of the surface 17. The result is that forwardly of the step 10 the boat is provided with a single central planing surface 16 and adjacent the stern is provided with a pair of relatively 25 widely spaced planing surfaces 18, and these three surfaces constitute substantially all of the wetted surface of the boat when the boat is planing properly on the surface of the water. The surfaces 18, being relatively 30 widely spaced from each other, impart great lateral stability to the boat which allows it to make relatively short turns at greater speeds than in the case of conventional constructions without danger of overturning, and the surfaces 18 being spaced longitudinally of the 35 boat from the surface 16 gives the boat longitudinal stability.

The surfaces 18, being spaced outwardly of the surface 16, are not affected by any disturbance of the water which may be set up 40 by the surface 16 passing over the same as is necessarily the case in conventional constructions, and inasmuch as the surfaces 18 therefore contact with relatively undisturbed water surface, the resistance to the passage of the same over the water is less than the rear planing surface in conventional constructions. Furthermore, in view of the fact that all of the planing surfaces are contacting 45 with undisturbed and undisplaced water, the boat will remain on a predetermined keel angle regardless of the speed thereof. This feature insures greater longitudinal stability of the boat than conventional constructions. 50 In addition, in view of the fact that the speed of the boat for a given power output is dependent upon the resistance of the air and water and a function of the angle of the planing surfaces of the boat relative to the 55 surface of the water multiplied by the unit

70 weight thereon, with the present design of boat the angle of the planing surfaces may be formed to achieve optimum conditions and will remain substantially constant throughout the range of speed of the boat.

The surface 17, which in effect extends the surface 16 rearwardly of the step 10, is preferably of a sufficient height so that the wave which often follows a planing surface in the water and is caused by the amount of necessary displacement of the surface in the water, is preferably of such a height that the following wave does not contact with it so as to add any increase in the wetted surface of the hull. In order to prevent any suction 75 building up back of the step 10 that might tend to aggravate the following wave and to draw water rearwardly thereof up into contact with the surface 17, or otherwise interfere with the free passage of the boat through 80 the water, bleeder tubes such as 20 may be provided for allowing the free passage of air from above the level of the water to the bottom of the surface 17 immediately to the rear of the step 10.

85 With this construction it will be apparent that the boat may be so designed that the planing surfaces 16 and 18 may be made of the minimum dimensions necessary to obtain proper planing without providing an excessive amount of wetted surface to obtain the desired lateral stability, and at the same time all of the surfaces contact with relatively undisturbed water surface. Although the forward section of the boat is shown as of a modified V-type, it will be apparent that the same may be of an inverted V-type in which the sides of the boat in the region of the bow are of a greater depth than the center portion 90 thereof, without anywise affecting the present invention, and it will also be apparent that the planing surfaces 16 and 18 may be made either slightly concave or convex and that the step 10 may be either straight transversely of the boat or else have its center portion 95 bent either forwardly or rearwardly of its ends in plan view without affecting the present invention. While it is also possible to construct the boat with the spaced planing surfaces adjacent the midpoint of the boat 100 and the single planing surfaces at the stern, I prefer to employ these planing surfaces in approximately the location shown in the drawings as I believe more lateral stability is 105 obtained thereby.

110 Formal changes may be made in the specific embodiment of the invention described without departing from the spirit or substance of the broad invention, the scope of which is commensurate with the appended 115 claims.

120 What I claim is:

1. A boat having but three longitudinally non-aligned planing surfaces formed on the bottom thereof, said planing surfaces being 130

- so arranged that lines connecting the centers of areas thereof form a triangle.
2. A boat having the bottom thereof formed to present only three major planing surfaces, one of which is spaced forwardly from the other two, and said other two surfaces being spaced from each other transversely of said boat, and out of overlapping relationship longitudinally of said boat with respect to the first mentioned surface.
3. A boat having the bottom thereof formed to present three planing surfaces only, one of which is spaced forwardly from the other two, and said other two surfaces being spaced from each other transversely of said boat by a distance approximately equal to the transverse dimension of the first mentioned surface.
4. A boat having three planing surfaces on the bottom thereof, one of which constitutes substantially half of the total planing surface area of said boat.
5. A boat having three planing surfaces on the bottom thereof, one of which constitutes substantially half of the total planing surface area of said boat and the other two planing surfaces having areas substantially equal to each other.
6. A boat having only three planing surfaces on the bottom thereof, one of which is spaced longitudinally of said boat from the other two thereof, and said other two planing surfaces being spaced from each other transversely of said boat.
- 35 7. A boat having only three planing surfaces on the bottom thereof, one of which is spaced longitudinally of said boat from the other two thereof, and said other two planing surfaces being spaced from each other transversely of said boat an amount at least equal to the width of the first mentioned planing surface.
8. A boat having only three planing surfaces on the bottom thereof, one of which is spaced longitudinally of said boat from the other two thereof, and said other two planing surfaces being spaced from each other transversely of said boat an amount substantially equal to the width of the first mentioned planing surface.

ALANSON P. BRUSH.
